UNITED STATES PATENT OFFICE.

CORA G. ECKET, OF LOS ANGELES, CALIFORNIA.

DESIGN FOR A FIGURE TOY.

57,518.

Specification for Design.

Patented Apr. 12, 1921.

Application filed October 19, 1920. Serial No. 418,107. Term of patent 14 years.

To all whom it may concern:

Be it known that I, CORA G. ECKET, a citizen of the United States, residing at Los Angeles, in the county of Los Angeles and State of California, have invented a new, original, and ornamental Design for a Figure Toy, of which the following is a specification, reference being had to the accompanying drawing, forming part thereof.

Fig. 2 is a back view thereof.

I claim:

The ornamental design for a figure toy as shown.

CORA G. ECKET.
